UNITED STATES PATENT OFFICE.

CHRISTIAN WILLIAM MEINECKE, OF JERSEY CITY, NEW JERSEY, ASSIGNOR
TO MEINECKE AND COMPANY, OF NEW YORK, N. Y., A CORPORATION
OF NEW JERSEY.

BOTTLE-STOPPER.

SPECIFICATION forming part of Letters Patent No. 709,418, dated September 16, 1902.

Application filed April 21, 1902. Serial No. 104,037. (No model.)

To all whom it may concern:

Be it known that I, CHRISTIAN WILLIAM MEINECKE, a citizen of the United States, residing at Jersey City, in the county of Hudson and State of New Jersey, have invented new and useful Improvements in Bottle-Stoppers, of which the following is a specification.

This invention relates to a method of securing a stopper to a water-bottle, ice-bag, or other receptacle in a simple and presentable manner, as set forth in the following specification and claims, and illustrated in the annexed drawings, in which—

Figure 1 shows a bottle-stopper embodying this invention applied to a hot-water bag or receptacle. Fig. 2 shows a chain-fastening ring before the same is applied or bent to its final position. Fig. 3 shows a modification. Fig. 4 shows another modification, the stopper being of the kind more generally applied to "ice-bags," so called.

In the drawings is shown a bottle or bag *a*, having a bushing or collar *b*, suitably cemented or secured to or within the mouth or neck part of the vessel or receptacle. A stopper *c* is adapted to be inserted into and withdrawn from the mouth or collar for opening or closing.

A chain *d* properly applied will prevent the stopper when open from becoming lost or detached from the vessel. When the stopper is inserted in the collar, the chain is inside the bag or concealed from view, so as not to cause any unsightliness. A presentable appearance is thus maintained. This attaching-chain is shown connected to the bottom of the stopper and to the interior of the vessel. The method of attaching the chain can be any suitable kind. At one end the chain can be connected to the stopper at the under projection or button-like stud used for holding a washer to the stopper, said stud having a swivel connection or suitable perforation or eye for the entrance or securing of a link or chain end, as seen at *e*, Fig. 1, or *e'*, Fig. 3. A swivel connection may be preferred, as preventing the chain from tangling. A swivel connection is shown at *e*, Fig. 1, applied to a threaded or screw stopper made to be screwed into a threaded bushing. An eye *e'* is shown in Fig. 3, or an eye or loop wire may connect the chain to the stopper, as seen at *e''*, Fig. 4.

The other end of the chain can be connected to the interior of the bottle or vessel in suitable manner. An attaching ring or wire *f* 55 can be clasped or secured about the collar and the chain connected to such wire or to an eye or depending portion *f'*, projecting into the interior of the bag from between the neck and collar. The chain could also be secured 60 to a side or edge portion of the bushing or collar, Fig. 4.

When the stopper is in place, the chain is concealed in the bag. When the stopper is withdrawn, one end of the chain remains secured 65 in the bag.

The chain being out of the way and out of sight when the stopper is closed, neatness of appearance and easy handling are attained, and no catching or rattling of the chain occurs.

What I claim as new, and desire to secure by Letters Patent, is—

1. A bottle or vessel having a threaded bushing and a stopper adapted to screw into 75 the bushing, an attaching wire or ring secured about the bushing, and a chain connected to the wire and to the bottom of the stopper.

2. A bottle or vessel provided with a stopper having a button-like projection at its under side, a swivel connection on said projection, and a securing-chain for the stopper connected at one end to the swivel connection and at its other end secured to the interior of the bottle.

3. A bottle or vessel having a threaded bushing secured in the neck thereof, a threaded stopper adapted to engage the bushing and provided on its lower face with a button-like projection, a swivel connection on said projection, a securing-chain for the stopper connected at one end with said swivel connection, and means connected to the bushing and attached to the other end of said chain for securing the chain within the interior of 95 the bottle or vessel.

In testimony whereof I have hereunto set my hand in the presence of two subscribing witnesses.

CHRISTIAN WILLIAM MEINECKE.
